UNITED STATES PATENT OFFICE.

EDWARD H. SPRINGER, OF SANTA MONICA, CALIFORNIA.

DESIGN FOR A DOLL-HEAD.

57,547.

Specification for Design.

Patented Apr. 12, 1921.

Application filed July 2, 1920. Serial No. 393,724. Term of patent 7 years.

To all whom it may concern:

Be it known that I, EDWARD H. SPRINGER, a citizen of the United States, residing at Santa Monica, in the county of Los Angeles and State of California, have invented a new, original, and ornamental Design for Doll-Heads, of which the following is a specification, reference being had to the accompanying drawing, forming a part thereof.

Fig. 2 is a rear elevation of the same.

I claim:

The ornamental design for a doll head as shown.

EDWARD H. SPRINGER.
